UNITED STATES PATENT OFFICE.

ELIAS WEINREICH, OF DAYTON, OHIO.

DESIGN FOR A CIGAR.

SPECIFICATION forming part of Design No. 28,058, dated December 21, 1897.

Application filed May 5, 1897. Serial No. 635,264. Term of patent 3½ years.

To all whom it may concern:

Be it known that I, ELIAS WEINREICH, a citizen of the United States, residing at Dayton, Montgomery county, State of Ohio, have 5 invented and produced a new and original Design for Cigars; and I do declare the following to be a clear, full, and exact description of the invention, such as will enable others skilled in the art to which it appertains to 10 make and use the same, reference being had to the accompanying drawings.

My design relates to cigars, and has for its object to improve their appearance. Such object I attain in this case by certain impressions in the form of grooves or corrugations imparted to the outside of the cigar.

In the drawings, Figure 1 shows an elevation of a cigar provided with my design. Fig. 2 is an enlarged cross-section thereof.

The design consists of two sets of parallel 20 grooves, the grooves of one set running at an angle to the grooves of the other, so as to produce the checkered appearance shown. Since these grooves are produced by pressure, the latter causes the cigar to assume a flat shape, 25 as shown in Fig. 2, and my design is imparted to these flat sides—that is, to the side shown in Fig. 1 and to the one opposite thereto.

Having described my design, I claim the same as follows:

The design for a cigar as herein shown and described.

In testimony whereof I hereunto affix my signature in presence of two witnesses.

ELIAS WEINREICH.

Witnesses:

C. SPENGEL,
ARTHUR KLINE.
